UNITED STATES PATENT OFFICE.

ARNOLD J. SCHEVERS, OF CHICAGO, ILLINOIS.

STEAM-BOILER CLEANER.

SPECIFICATION forming part of Letters Patent No. 768,152, dated August 23, 1904.

Application filed May 16, 1903. Serial No. 157,390. (No model.)

To all whom it may concern:

Be it known that I, ARNOLD J. SCHEVERS, a citizen of the United States, residing at Chicago, in the county of Cook, State of Illinois, have invented certain new and useful Improvements in Steam-Boiler Cleaners; and I hereby declare the following to be a full, clear, and exact description of the same, reference being had to the accompanying drawings, in which—

10 Figure 1 is a perspective in full line of devices embodying my invention and in dotted line of the portions of a locomotive-boiler surrounding said devices. Fig. 2 is a sectional view of the lower part of one of the water-legs of the boiler and the steam-pipe therein.

Like symbols refer to like parts wherever they occur.

My invention relates to the construction and arrangement of that class of devices intended for use in connection with steam-boilers for preventing the adherence of sediment, mud, &c., to the boiler-sheets and for stirring up or disturbing any deposit thereof at the time that the boiler-water is drawn or blown off for the removal of sediment, mud, &c.; and to this end it consists, generally stated, in a system of perforated pipes arranged with relation to the fire-box, water-legs, and boiler-flues and connected with a source of fluid-pressure, substantially as will hereinafter more fully appear, whereby the usual points of deposit within the boiler may be swept by jets of fluid under pressure to displace the sediment therefrom and cause it to mingle with the boiler-water.

I will now proceed to describe my invention more fully, so that others skilled in the art to which it appertains may apply the same.

In the drawings, A indicates the fire-box portion of a locomotive-boiler, having the usual water-legs *a a* inclosing the fire-box.

B indicates the cylindrical portion or boiler proper, through which pass the fire-tubes *b b*, leading from the fire-box to the smoke-box, and C indicates the steam-dome, all of which may be of the usual or any approved construction, and the boiler-section B may be provided with the usual mud-drum M and blow-off cocks.

1 indicates the pressure or induction pipe connected with any suitable source of fluid-

pressure and entering the boiler through the back sheet at a point above the crown-sheet of the fire-box, at which point it is provided with a suitable valve 2 for cutting off or admitting the fluid-pressure to the system within the boiler.

3 indicates the first section of pipe within the boiler, which is the crown-sheet section and is located centrally over and extends the length of the crown-sheet of the fire-box and is perforated on its under side, so as to direct divergent jets against the top of the fire-box crown-sheet, the current established thereby being outward toward the water-legs *a a*, formed by the side-sheets of the inner and outer boiler-shell.

4 indicate vertical pipes arranged within the water-legs of the boiler about the middle of the fire-box and connected at their upper ends by a four-way coupling or otherwise with the induction-pipe 3 and at their lower ends with the horizontally-disposed loop-pipe 5, which encircles the fire-box near the bottom of the water-legs *a a*. The pipes 4 are so perforated laterally as to deliver jets against the inner and outer sheets of the side walls of the boiler, while the water-leg loop or section of piping 5 is perforated on its under side like section 3 to deliver downwardly-diverging jets toward the angles formed between the side walls and bottom of the water-legs.

6 indicates a vertical pipe (or riser) arranged in the water-space between the front sheet or waist and the shell of the fire-box, which pipe is connected at its lower end with the loop-pipe 5, which encircles the fire-box, and at its upper end with the cylinder loop-pipe 7, which extends forward toward the mud-drum in the cylinder-section B of the boiler and is arranged below the fire-tubes *b b*.

The vertical pipe 6 or riser is perforated laterally, so that its jets may sweep both shells of the water-chamber in which it is located, and the cylinder-loop 7 is perforated on its under side, as in the case of sections 3 and 5, where the intent is to disturb the sediment deposited on the horizontal surfaces which lie beneath.

I prefer to use steam from any suitable source as the fluid-pressure for stirring up the

mud and sediment within the boiler at the time of the blow-off; but if air or water jets are desired the induction-pipe 1 may be connected with a suitable source of air or liquid 5 under pressure.

The system of perforated pipes and their arrangement with relation to the boiler and its fire-box being substantially such as hereinbefore set forth, whenever the boiler is to 10 be blown off the blow-off cock is first opened, after which the valve 2 will be turned to admit the fluid-pressure from pipe 1 to pipe 3 over the crown-sheet of the fire-box, whence it will pass by pipes 4 4, water-leg loop 5, and vertical pipe 6 to cylinder-loop 7, escaping throughout its course in diverging jets, which forcibly impinge on the crown-sheet of the fire-box, the side walls and bottom of the water-legs of the boiler, and the bottom of the boiler 15 20 between the fire-box and the mud-drum, stirring up the sediment, which is caught and carried toward the mud-drum M or blow-off cocks in the boiler-water current which has been thus induced.

25 Where water-jets are employed and the pipe 1 is connected with some source of liquid under pressure, as hereinbefore noted, the blow-off cock will be opened, as before mentioned, and all steam allowed to escape from the boiler, 30 so that the boiler shall be entirely free of steam before the washing out is attempted.

Having thus described my invention, what I claim, and desire to secure by Letters Patent, is—

35 1. In combination with a steam-boiler having a mud-drum or blow-off cock, a boiler-cleaner comprising a system of connected piping arranged to inclose the fire-box and extending toward the mud-drum of blow-off 40 cock, said pipe being perforated to deliver divergent jets upon the crown-sheet and side walls of the fire-box, and means independent of the boiler for inducing fluid-pressure within said system of piping, substantially as and 45 for the purposes specified.

2. In combination with a steam-boiler having a mud-drum or blow-off cock, a system of connected piping arranged to inclose the fire-

box and comprising a crown-sheet pipe and water-leg loop both of which are perforated on their under sides to deliver downwardly-divergent jets, and means independent of the boiler for inducing fluid-pressure within said system of piping, substantially as and for the 50 purposes specified.

3. In combination with a steam-boiler having a mud-drum or blow-off cock, a system of connected piping arranged to inclose the fire-box and comprising a crown-sheet pipe perforated on its under side to deliver outwardly and downwardly-divergent jets, a water-leg loop perforated on its under side to deliver outwardly and downwardly-divergent jets, and lateral pipes which connect the crown-sheet pipe and water-leg loop, said lateral pipes 60 65 perforated to deliver laterally-divergent jets, and means independent of the boiler for inducing fluid-pressure within said system of piping, substantially as and for the purposes specified.

4. In combination with a steam-boiler having a mud-drum or blow-off cock, a system of connected piping comprising a crown - sheet pipe perforated on its under side to deliver outwardly and downwardly-divergent jets, a 70 water-leg loop perforated on its under side to deliver outwardly and downwardly-divergent jets, lateral pipes which connect the crown-sheet pipe and water-leg loop perforated to deliver laterally-divergent jets, said crown-sheet pipe, water-leg loop and lateral pipes arranged to inclose the fire-box, a cylinder-loop perforated on its under side to deliver divergent jets, a riser-pipe which connects the water-leg loop and the cylinder-loop, and means independent of the boiler for inducing fluid-pressure within said system of piping, 75 80 85 substantially as and for the purposes specified.

In testimony whereof I affix my signature, in presence of two witnesses, this 14th day of May, 1903.

ARNOLD J. SCHEVERS.

Witnesses:

DANIEL B. MASON,
ALBERT J. BUCKLEY.

It is hereby certified that in Letters Patent No. 768,152, granted August 23, 1904, upon the application of Arnold J. Schevers, of Chicago, Illinois, for an improvement in "Steam-Boiler Cleaners," an error appears in the printed specification requiring correction, as follows: In line 39, page 2, the word "of" should read *or*; and that the said Letters Patent should be read with this correction therein that the same may conform to the record of the case in the Patent Office.

Signed and sealed this 6th day of September, A. D., 1904.

[SEAL.]

F. I. ALLEN,
Commissioner of Patents.
